(57) **CLAIM**

The ornamental design for a packaging container, as shown and described.

DESCRIPTION

FIG. 1 is a front view of a packaging container, a back view being a mirror image thereof;

FIG. 2 is a top view thereof;

FIG. 3 is a bottom view thereof;

FIG. 4 is a right side view thereof, a left side view being a mirror image thereof;

FIG. 5 is a perspective view thereof; and,

FIG. 6 is a cross-sectional view thereof, taken along line 6-6 in FIG. 1.

In the drawings, the evenly-spaced broken lines show portions of a packaging container that form no part of the claim. In FIG. 1, the dash-dot-dash broken line arrow represents a sectional designation that forms no part of the claim.
